UNITED STATES PATENT OFFICE.

LOUIS P. BOUVIER, OF TORONTO, CANADA, ASSIGNOR OF ONE-HALF TO
WILLIAM H. BORK, OF BUFFALO, NEW YORK.

ENVELOPE-MACHINE.

SPECIFICATION forming part of Letters Patent No. 453,436, dated June 2, 1891.

Application filed January 2, 1891. Serial No. 376,512. (No model.)

To all whom it may concern:

Be it known that I, LOUIS PETER BOUVIER, of the city of Toronto, in the county of York, in the Province of Ontario, Canada, have invented a certain new and useful Improvement in Envelope-Machines, of which the following is a specification.

The object of the invention is to arrange a device to assist the carrier in supporting the blank as it is carried from the picker to the folding-plunger; and it consists in the peculiar construction, arrangement, and combinations of parts hereinafter more particularly described, and then definitely claimed.

15 The drawing represents a perspective view of the carrier of an envelope-machine.

The side bars A and the cross-bar B of the carrier are made and operated in the usual manner.

20 C is a centrally-located bar, having an ear C at one end, through which is passed the shaft D. From this shaft the center bar C extends to a point below the rear flap of the blank E, the said bar C resting in grooves 25 made in the creasing-box G, one of said grooves being hidden on the drawing by the folding-plunger F. A spring H is provided for the purpose of holding the center bar C down in position.

30 It will be observed that the front flap of the blank E rests upon the cross-bar B, while the side bars A support the side flaps of the said blank. So far this is the usual plan for supporting the blank E; and my improvement 35 consists in providing the center bar C, the end of which extends below the rear flap of the blank E, as indicated. The carrier, as shown in the drawing, is in the position it

should be when just about to carry the blank from the picker to the folding-plunger F. 40 When the carrier moves back and has conveyed the blank E immediately below the plunger F, the end a of the bar C is behind and clear of the plunger F, so that the said plunger may descend in the usual manner 45 and carry the blank E with it. When the plunger F has descended with the blank, the carrier returns to the picker for a fresh blank. It follows, therefore, that the bar C when in this latter position would be in the road of 50 the plunger if some provision in the form of the plunger were not made to avoid the said bar. With that view I divide the plunger in the center, making a double-headed plunger, with sufficient space between the two parts to 55 allow them to pass the bar C.

What I claim as my invention is—

1. The combination, with the creasing-box and carrier of an envelope-machine, of a central bar located and arranged to support the 60 rear flap of the envelope-blank and moving in a groove in said creasing-box, substantially as and for the purpose specified.

2. The envelope-blank carrier having a center bar C and cross-bar D, the center bar C 65 being pivotally connected to the cross-bar D and held in a groove made in the creasing-box G by the spring H, in combination with said grooved creasing-box and spring, and a double-headed folding-plunger F, arranged 70 substantially as and for the purpose specified.

Toronto, December 23, 1890.

LOUIS P. BOUVIER.

In presence of—

CHARLES C. BALDWIN,
JOHN E. CAMERON.
